UNITED STATES PATENT OFFICE.

JONATHAN P. B. FISKE, OF ALLIANCE, OHIO.

DESIGN FOR A CASING FOR ELECTRIC CONTROLLERS.

SPECIFICATION forming part of Design No. 24,427, dated June 25, 1895.

Application filed January 10, 1895. Serial No. 534,493. Term of patent 7 years.

To all whom it may concern:

Be it known that I, JONATHAN P. B. FISKE, a citizen of the United States, residing at Alliance, county of Stark, and State of Ohio, have invented and produced a new and original Design for a Casing for Electric Controllers, of which the following is a specification, reference being had to the accompanying drawings, forming a part thereof.

10 My invention relates to a design for easings for electrical controllers, and consists in a design for a frame or casing for an electrical controller as hereinafter described and shown in the accompanying drawings.

15 Figure 1 of the drawings is a side elevation, and Fig. 2 an edge view, of the frame or casing.

A represents the body portion of the frame or casing having a rounded top B and flat sides.

20 The base C of the frame or casing is flat and rectangular in form and its bottom face

is recessed to form feet at the ends of said base.

The flat angular base C projects beyond the ends of the body portion A and also laterally 25 from the sides thereof.

The leading features of my design comprise the casing for an electrical controller having a round top, flat sides and a flat rectangular base recessed in its bottom to form feet at the 30 ends of said base, said base projecting beyond the ends of the body portion and laterally therefrom.

What I claim is—

The design for a casing for an electric controller, substantially as herein shown and described. 35

JONATHAN P. B. FISKE.
